ALFRED ALSAKER AND ERIC NORDHEM, OF CHICAGO, ILLINOIS, ASSIGNORS TO THE DELTA STAR ELECTRIC COMPANY, OF CHICAGO, ILLINOIS, A CORPORATION OF ILLINOIS

LOCKING-TYPE SWITCH-OPERATING HANDLE

Application filed November 3, 1927. Serial No. 230,760.

This invention relates to switch operating means, and more particularly to a handle adapted for connection to a switch remote from the handle through a suitable system of links and levers, means being provided for locking the handle in any one of several selected positions.

Our invention has to do primarily with the locking means for securing the handle structure in adjustment. By our invention we provide a key operated lock and means associated therewith whereby the handle structure can be positively locked against operation so as to effectually prevent unauthorized opening or closing of the switch. In conjunction with the locking means we also provide, in one form of the device, electro-responsive means for preventing release of the handle structure by operation of the key operated lock until such time as the oil switch, or other apparatus used for interrupting the line current and situated remote from the disconnect switch which is operated by the handle structure, has been opened. After this has been done, the electro-responsive means is actuated to permit release of the handle structure for closing or opening the disconnect switch. We also contemplate a further modification in which an auxiliary 30 switch controlling one or more interlocking or signalling circuits is connected to the lock controlled means in such manner that the condition of the disconnect switch operated by the handle structure will be properly indicated at a point remote from the handle structure, and the fact that the handle is to be operated for closing or opening the disconnect switch will be signified at such point before operation of the handle structure actually takes place. Further objects and advantages will appear from the detailed description.

In the drawings:—

Fig. 1 is an elevation of a handle structure 45 in accordance with our invention;

Fig. 2 is a side view of the handle structure;

Fig. 3 is a vertical section through the supporting base and the switch housing taken from front to back, parts being shown in elevation;

Fig. 4 is a back view of the supporting base and associated parts, partly broken away and in section;

Fig. 5 is a horizontal section through the handle structure and arm and the supporting base;

Fig. 6 is a section taken substantially on line 6—6 of Fig. 4, on an enlarged scale;

Fig. 7 is a transverse section through the supporting base taken in the plane of the lock and the locking cam member, parts being shown in elevation;

Fig. 8 is a transverse sectional view through the switch housing taken adjacent the upper end thereof and looking down;

Fig. 9 is a section taken substantially on line 9—9 of Fig. 8;

Fig. 10 is a section taken through the auxiliary switch structure substantially on line 10—10 of Fig. 9;

Fig. 11 is a section taken substantially on line 11—11 of Fig. 10;

Fig. 12 is a section taken substantially on line 12—12 of Fig. 10;

Fig. 13 is a section through the supporting base and associated parts showing the stop elements for preventing and limiting entry of the pawl into the apertures of the hub of the handle member, the auxiliary switch and associated parts being omitted;

Fig. 14 is a perspective detail of one of the pawl limiting members;

Fig. 15 is a vertical central sectional view through the supporting base and associated parts from front to back of the base, illustrating the second modified form, parts being shown in elevation;

Fig. 16 is a side view of the form of operating handle structure illustrated in Fig. 15;

Fig. 17 is a section taken substantially on line 17—17 of Fig. 16;

Fig. 18 is a section taken parallel to and adjacent the cover of the electromagnet housing in the form shown in Fig. 15, the base being shown fragmentarily;

Fig. 19 is a vertical central sectional view through the lower portion of the base and the electromagnet housing, parts being shown in elevation;

Fig. 20 is a section through the electromagnet housing and associated parts taken substantially on line 20—20 of Fig. 18;

Fig. 21 is a diagram showing the lock actuated switch connected to control an oil switch, the signalling circuits controlled by the lock switch being omitted for clearness; and

Fig. 22 is a diagram of the connections for the electromagnetic lock used in the switch illustrated in Figs. 15 to 20.

The device includes a base member 1 having a flange 2 secured by means of cap screws 3, or in any suitable or preferred manner, to a base member or block 4, adapted to be secured to a wall support in any suitable manner. Base member 1 is provided in each side thereof, with a forwardly projecting standard 5 carrying a bearing sleeve 6. A short length of tubing forming a shaft 7 is rockably mounted through the bearings 6 and projects beyond the same to one side of base member 1. An operating arm 8 is secured on the projecting portion of shaft 7 by means of U-bolts 9 and set screws 10. This arm is bifurcated to receive one end of a curved link 11 pivotally secured between the members of arm 8 by a pin 12 held against endwise movement by cotter pins, or in any other suitable manner. Operating arm 11 is provided at its other end with a socket member 13 in which is secured an operating rod 14, the other end of which is connected, in any suitable manner, to a suitable system of links and levers for operating a disconnect switch disposed at a point remote from the operating handle structure. By rocking the shaft 7 about its axis into its extreme position in either direction, the switch can be easily opened or closed, as required.

Shaft 7 is operated by a handle structure 15. This structure includes a rod or shank 16 provided at its upper end with a spade handle 17. A hub 18 is provided at the lower end of shank 16, this hub having a socket member 19 in which the shank 16 is secured by rivets 20 (Fig. 3) or in any other suitable manner. The hub 18 is bored and threaded, adjacent socket member 19, for reception of dog point set screws 21, the points of which enter corresponding openings in shaft 7. This serves to effectually secure the handle structure to the shaft for operating the latter.

Hub 18 is provided with a plurality of openings 22 disposed radially thereof and

adapted for reception of a nose element 23 of a holding pawl 24 rockably mounted on a pin 25 extending transversely of the base 1 above shaft 7. It will be noted that the openings 22 are of approximately segmental shape and converge inwardly of the hub, the element 23 being shaped similarly to the opening and of somewhat less width. This renders it possible to force element 23 out of the opening 22 when the pawl 24 is released by exerting appreciable pressure on the contacting inclined surfaces of element 23 and the wall of opening 22 with which this element contacts. It will thus be seen that, when the pawl is released, the hub 18 can be turned into either position desired by first releasing it from the pawl which may be readily accomplished by exerting a slight pull upon the handle 17.

For locking the pawl 24 in holding or operative position I provide a cam 26 from one side of which extends a stub shaft 27 which is rockably mounted in a tubular boss 28 projecting inwardly from one side of the base member 1. This cam is positioned and adapted to be turned into and out of operative relation to a finger element 29 extending from the free end of pawl 24, the lower portion of this element being provided with an arcuate recess for reception of the cam. When the cam is in operative position, the pawl is effectively held against outward movement and is retained in operative position with the element 23 disposed in one of the openings 22 locking the hub, and, consequently, shaft 7, in adjustment. By turning the cam into inoperative position the pawl is released and can be moved out of operative engagement with the hub in the manner previously described.

A key operated lock 30 is mounted in the other side wall of the base member 1. This lock includes an outer flange 31 and a body 32 which passes through an opening in wall 1A, this body being provided, at its inner end, with outwardly projecting diametrically opposite lugs 33. A U-shaped clamp 34 straddles body 32, this clamp being provided at the end of each arm with a rounded finger 35 bearing upon the inner face of wall 1A. A pressure screw 36 is threaded through the bight portion of the clamp and bears against the bottom wall of a recess provided in wall 1A for reception of this screw. This provides simple and efficient means for securing the lock in the base member.

The lock used is a standard make of Yale lock made by the Yale & Towne Company. This lock is of the cylinder type and includes a rotary barrel or cylinder 37 which projects inwardly beyond the inner end of body 32, this cylinder receiving at its outer end the key, rotation of the cylinder when the key is withdrawn being prevented by the pins or tumblers of the lock in a known manner.

Cylinder 37 is connected to cam member 26 by a connecting rod 38. This rod is provided at one end with an L-shaped member 39, one arm of which engages into a recess in cylinder 37. An angle plate 40 fits about the lower portion of cylinder 37, as considered in Fig. 7, and is secured to the cylinder by a screw 41. This plate abuts the flat surface of the outer arm of member 39 and serves to hold this member against undesirable looseness or play. At its other end the rod 38 is provided with a diametrically extending rib 42 from the central portion of which projects a reduced pin 43. Rib 42 fits into a groove 44 provided in the inner face of cam 26 and the pin 43 extends into a recess or bore extending from the bottom of this groove. In this manner the cylinder of the lock and the cam member 26 are operationally connected together so that the cam member will turn with the cylinder and will be secured by the cylinder against turning movement when the key of the lock is withdrawn and the cylinder is locked against movement. The lock thus forms key operating means for operating and controlling the cam member and, consequently, the release and locking of the handle structure.

A coiled torsion spring 45 is mounted about rod 38 and is confined between the cam and an eye 49 of an arm 50 the other end of which fits into a groove in a pin 51 projecting laterally from pawl 24 (Fig. 4 and Fig. 6). A finger 52 extends inwardly from eye 49 at right angles thereto. This finger is provided in its inner edge with a notch (Fig. 5) which receives one end of the torsion spring 45. The other end of the spring engages about a pin 53 projecting inwardly from the inner face of cam 26. By reference to Fig. 3 it will be seen that the torsion spring urges the cam member in a clockwise direction and the arm 50 in a counterclockwise direction so as to urge the pawl 24 toward hub 18. Movement of the cam in clockwise direction will be limited by movement of the cylinder of the lock which is not permitted to turn in such direction beyond full locking position. If desired, the cam member may be provided with a stop element or pin disposed for contact with the terminal element 29 of the pawl for limiting movement of the cam member in locking direction though, under ordinary conditions, we do not deem this necessary. With the parts in the positions shown in Fig. 3, the handle structure and shaft 7 are effectually held by the pawl 24 in switch closing position. When it is desired to open the switch, the key is inserted in the lock and the cylinder thereof is turned in proper direction to turn the cam member through an arc of approximately 180 degrees in a counterclockwise direction, as considered in Fig. 3, releasing the pawl 24 and permitting movement there-

of away from the hub sufficiently to disengage element 23 from its recess. After the hub has been turned a short distance, the key in the lock may be released, as return of the pawl to locking position will be prevented by contact of element 23 with the hub. When the shaft has been turned into full switch opening position, the other recess or opening 22 of the hub is brought into alignment with element 23 of the pawl which is then moved inwardly by the spring to position element 23 in the opening. This releases the cam member which is then returned to locking position by the spring. In this respect the locking mechanism is automatic in its operation in that it is held inoperative during movement of the shaft from either of its extreme positions to its other extreme position, and is then actuated by the spring to lock the shaft against movement. We have shown the hub 18 as provided with a third recess or opening 22A midway between the two openings 22. This central opening may be employed whenever it is found necessary or desirable, because of restricted space or for other reasons, to lock the handle structure in substantially horizontal position, that is, in position midway between its two extreme positions. When it is not desired to use the opening 22A it may be closed or rendered inoperative by means of an arcuate closure plate 54 of a size to fit snugly in the outer portion of this opening, this plate being secured in position by a screw 55 passing therethrough and threading into a clamping plate 56 disposed inside of the body of hub 18 between the same and shaft 7. To accommodate this clamping plate the hub 18 is provided, at each end thereof, with an inwardly projecting flange 18A, these flanges and the body of the hub enclosing an annular space 57 about the shaft. This structure will be clear from reference to Fig. 5. At times it is desirable to provide means whereby the key cannot be withdrawn from the lock except after the switch is closed. It is also often convenient to permit the key to remain in the lock, particularly when the switch is to be open but a short length of time, as this prevents loss of the key and insures that it is readily available when it is desired to close the switch. With this object in view we provide means whereby entry of the element 23 of pawl 24 into the opening 22 is limited. In Figs. 13 and 14 we have illustrated a stop member including an arcuate base 58 and a body 59 of a size to be inserted into the inner portion of opening 22 from inside the hub. The base 58 corresponds in thickness to the width of space 57 radially of the hub and is disposed concentric with the shaft and the hub. This member is applied before the hub is mounted on the shaft and is held in position by the shaft, as will be clear from

Fig. 12. With the stop member in position as illustrated, when the shaft 7 is turned into its other extreme position from that shown in Fig. 13, i. e., into switch opening position, the element 23 of pawl 24 will enter opening 22 and will contact with body 59 limiting movement of the pawl toward the hub. This disposes terminal element 29 of the pawl so that the recess in this element is eccentric to the cam and will permit turning of the cam in locking direction sufficiently to lock the pawl against outward movement while preventing turning of the cam into full locking position. This serves to lock the hub against movement in either direction and also prevents withdrawal of the key from the lock, it being understood that the key cannot be withdrawn from the lock until the cylinder of the lock has been turned into full locking position in accordance with the common practice in locks of this type. When it is desired to close the lock, the lock is operated to release the pawl and the handle structure is then returned to switch closing position, after which the key is released and the cam is returned by the torsion spring to full operative or locking position, after which the key may be withdrawn from the lock.

It is frequently desirable to notify parties at a sub-station or some point remote from the disconnect switch, of the condition of the switch, that is, whether the switch is closed or open. It may also be found desirable to provide means for notifying parties at the disconnect switch operating handle of the condition of the line switch. With these objects in view, we contemplate providing an auxiliary switch controlling signalling or interlocking circuits, this auxiliary switch being operated by the lock operated means for securing the holding pawl. A switch housing 60 of rectangular shape in transverse and longitudinal section is secured to the lower wall of base member 1 by cap screws 61 passing through two flanges 62 projecting inwardly from the upper ends of the side walls of the housing, these cap screws threading through the lower end wall of base member 1. The inner portion of housing 60 is cut away at the upper end thereof to accommodate flange 2A of base member 1, this flange being also provided with openings for reception of cap screws for securing the base member to the wall member or block 4. The outer side of the housing is closed by a cover plate 63 secured thereto by screws 64 passing through the plate and threading into bosses 65 projecting from the housing adjacent each forward corner thereof. The housing is further provided with two bosses 66 projecting inwardly from approximately the longitudinal central portion of each side wall of the housing, these bosses being disposed further away from the front of the housing than

the bosses 65. A supporting strip 67 extends transversely of housing 60 and is secured to bosses 66 by screws 68. This strip supports a switch structure 69 secured thereto by screws 70, the switch being a double pole, double throw type of switch. The construction of the switch is more clearly illustrated in Figs. 8 to 12. The switch includes a central rectangular frame 71 of phosphor-bronze or other suitable material. Cap plates or closure members 72 formed of a synthetic resin commercially known as bakelite, or any other suitable or preferred insulating material, are secured to the opposite sides of frame 71 by screws 73 passing through the plates and threading into the thickened corners of the frame. An operating rod 74 is slidably mounted through the ends of the frame 71, the free end portion 75 of this rod being reduced in diameter, as illustrated in Fig. 9. Rod 74 threads through the central portion of a block 76 of any suitable insulating material, such as fiber, the synthetic resin known as bakelite, etc. This block is provided, adjacent each end, with a bore extending through the block from side to side thereof. A short pin 77 of fiber or other electrical insulating material is slidably mounted in each bore and is urged outwardly by an expansion coil spring 78, also mounted in the bore. The pins and the springs are confined between two contact strips 79 of copper or other suitable electrical conducting material, these strips seating in rectangular grooves 80 extending from front to back of the lateral faces of the block and intersecting the bores thereof. Each strip 79 is provided, in its inner face and adjacent each end, with a recess 81, these recesses receiving the end portions of the pins 77 and the springs 78 which seat therein. Movement of the contact strips 79 away from the block 76 is positively limited by the plates 72. The springs and the pins act to press the strips outwardly into contact with the plates 72 and also serve to hold these strips against endwise movement. As will be noted more clearly from Fig. 12, the springs and the pins in the bores of the block are oppositely related so that each contact strip is held in position and urged outwardly by a pin and a spring in direct engagement therewith.

A plurality, in this case four, of terminal members 82 are secured in each of the plates 72. Each of these terminal members is bored and threaded for a screw 83 for securing the end of a wire or conductor, and is provided on its inner end with a flat head 84 disposed in a channel 85 milled out from the inner face of plate 72, the terminal members being disposed in pairs aligned transversely of the plates from front to back thereof. The inner faces of heads 84 of the terminal members are flush with the inner faces of the

plates 72, so that, upon movement of the block 76 into its extreme position in either direction, two sets or pairs of the terminal members are connected electrically through the contact strips 79. This provides simple and efficient means for controlling a plurality of interlocking or signalling circuits by movement of the block 76. By referring to Fig. 3, it will be noted that the switch operating rod 74 is connected by a link 86 to pin 53 of the cam 26. When the handle structure is in position closing the disconnect switch, the block 76 is raised and the contact strips close the proper circuits to signify this fact. When it is desired to open the contact switch it is necessary to first unlock the holding pawl 24 by turning the cam member in a counterclockwise direction, as considered in Fig. 3, through an arc of approximately 180 degrees. This movement of the cam member serves to move the block 76 into its lower position closing the circuits controlled by the lower pairs or sets of terminal members and signalling the intention to open the disconnect switch. If, for any reason, the disconnect switch should not be opened, this fact can be signified by a suitable signal operated from a sub-station or some point remote from the switch operating handle structure, this signalling means being included in one of the circuits controlled by the auxiliary switch. In this connection it is important to note that the pawl 24 is not released until after the block 76 has been lowered sufficiently to connect the lower terminal members through the contact strips 79. Movement of the insulating block in either direction is limited by abutment elements 87 adjacent the corners of frame 71. The threaded connection between the operating rod 74 and the block permits of adjustment between these two members to obtain accuracy in operation of the switch without interfering with the proper operation of the cam 26, and the connections between the movable member of the switch and the cam assure that the switch will be operated only at proper times and by a properly authorized person.

In Figs. 15 to 20 we have illustrated a modified form in which the opening of the disconnect switch can be positively prevented from a point remote from the operating handle structure. A latch 88 is pivoted at one end at 89 on a pin 90 projecting from the lower wall of base member 1. This latch is loosely connected at 91 to one end of a rod 92, the other end of which is secured to one arm of an L-shaped lever 93 secured in a U-shaped stirrup 94 rockably mounted on a pin 95 extending transversely of a housing 96 secured to the lower end portion of base member 1.

An electromagnet of suitable type is mounted within the housing 96. This electromagnet includes a core formed of two sub-

stantially U-shaped members 97, the outer arms of which are secured by screws 98 to brackets 99 secured by screws 100 to the inner wall of the housing. The inner arms of the members 97 are secured together in any suitable manner as by riveting (Fig. 20) and these members form a core within which is disposed the coil 101. The terminals of this coil are connected to binding posts 102 carried by a cross bar 103 of any suitable electrical insulating material such as the synthetic resin known as bakelite, this bar being secured between the side walls of the housing in any suitable manner as by screws 104. A cover plate 105 is secured over the front of housing 106 by means of screws 107 passing through this plate and threading into the members 97, this plate being provided with suitably disposed flanges about its periphery for properly positioning it. The lever 93, as well as the rod 92 and latch member 88 are preferably made of brass or other suitable non-magnetic material, and an armature 107 of soft iron or other suitable magnetic material is secured across the lower end of the lever 93 and is disposed adjacent and in alignment with the inner pole of the electromagnet. The electromagnet is normally energized so as to hold the armature 107 in its raised or outer position. This holds the lever in rocked position about its pin 95 and disposes the bill 88A of latch member 88 in position for engagement with a pin 108 secured in cam 26 and projecting therefrom at the same side as the pin 53. This pin 108 is so disposed as to engage with the latch member before the cam has been turned into full unlocked or pawl releasing position. It will thus be seen that it is impossible to release the handle structure until the circuit through the coil of the electromagnet is broken. This circuit is preferably so arranged that the electromagnet is energized continuously as long as the line switch is closed. This provides a very effective safety control which will prevent opening of the disconnect switch until the line circuit has been broken or opened.

In Fig. 21 we have illustrated diagrammatically the application of our operating handle and associated lock actuated switch to a high tension bus circuit the diagram being of the conventional one line type, the disconnect switch being indicated as gang operated. When handle 15 is raised, as indicated in dotted lines, the disconnect switch 110 is closed, closing the bus circuit from bus 111 through wire 112 to the oil switch 113, from which it extends to the load after the oil switch is also closed. To open the disconnect switch it is necessary to first operate lock 72 to turn the cam 26 into inoperative position to release the pawl 24. This moves strip 79 into contact with the contact members 84. The circuit of the trip coil (not shown) of the oil switch is then closed 130

from the positive operating bus 114 through wire 115, strip 79, lead 116, wire 117, trip wire 118, the trip coil, and the common wire 119 to the negative bus 120. This opens the oil switch before it is possible to open the disconnect switch, rendering it impossible to open the disconnect switch under load. As the handle 15 reaches its full switch opening position, the contact strip 79 is returned to raised or inoperative position, permitting closing of the oil switch. Before the handle can be returned to switch closing position it is necessary to again operate the lock 72 closing the circuit of the trip coil of the oil switch as before and opening the oil switch before it is possible to close the disconnect switch. It will thus be seen that, by the provision of the lock actuated switch and associated parts, we provide simple and efficient means for preventing either opening or closing of the disconnect switch under or on load.

An overload relay 121 is connected to the high tension bus wire 112 through a suitable transformer in a known manner. This relay acts to normally hold a contact strip 122 away from contacts 123 which are connected in shunt with wire 115 and about contact members 84. In the event of an overload, the strip 122 is shifted into position to bridge the contacts 123 closing the circuit of the trip coil of switch 113 from positive bus 114 through wire 115, wire 117 and strip 122, trip wire 118 to the coil, and common wire 119 to the negative bus 120. As the overload relay is shunted around the lock actuated switch of the operating handle, it can operate at any time regardless of the condition of the disconnect switch.

A control switch 124 is provided for opening and closing the oil switch. When the control switch is on contact 125 the circuit of the closing coil of the oil switch is closed from positive bus 114 through wire 126, closing wire 127 and the closing coil to the common wire 119, and through wire 119 to the negative bus 120. To open the oil switch, control switch 124 is moved into contact 128 from which extends trip wire 118. This closes the circuit of the trip coil from positive bus 114 through wire 126 and switch 124, trip wire 118, the trip coil, and through the common wire 119 to the negative bus 120, opening the oil switch.

Two pilot lights, one red and one green, as indicated, are connected in series with wire 126 and wires 118 and 127, respectively. When switch 124 is open both of these lights are illuminated, their circuits being closed through the trip coil and the closing coil, respectively, of the oil switch. The resistance of these lights is sufficiently high to prevent the flow of sufficient current to the coils to operate the switch, as is well understood in this art. When switch 124 is in

engagement with contact 125 for closing the oil switch, it shunts the green light which is thus extinguished, leaving only the red light illuminated. Upon movement of switch 124 into engagement with contact 128 to open the oil switch, the red light is shunted, leaving only the green light on. These lights are suitably disposed to indicate to the operator the condition of the control switch and, consequently, of the oil switch.

In Fig. 22 the disconnect switch is shown as closed. The coil 101 of the electromagnet is energized through the medium of a potential transformer 130, the primary coil of which is connected at one end to wire 112, the other end of this coil, as well as the corresponding end of the secondary coil, being grounded at 131. The other end of the secondary coil of the transformer is connected to one end of coil 101 which has its other end grounded at 132. When the oil switch is closed, the electromagnet is energized preventing opening or closing of the disconnect switch in the manner previously described. This renders it impossible to either open or close the disconnect switch under or on load.

As above indicated, and as will be understood by those skilled in the art, changes in construction and arrangement of parts of our invention may be resorted to without departing from the field and scope of the same, and we intend to include all such variations, as fall within the scope of the appended claims, in this application in which the preferred forms only of our invention have been disclosed.

What we claim is:—

1. In switch operating means, a handle structure including a hub mounted for turning movement, a pawl, said hub and the pawl having co-acting means for locking the hub in adjustment, said pawl being biased to the locking position, and cam means for rigidly holding the pawl in the locking position. 105

2. In switch operating means, a handle structure including a hub mounted for turning movement, a switch operating arm having operative connection with the hub, a holding pawl adjacent the hub, said pawl and the hub having co-acting means for holding the hub in adjustment, and means for locking the pawl against retraction from the holding position. 115

3. In switch operating means, a handle structure including a hub mounted for turning movement, a switch operating arm having operative connection with the hub, a holding pawl adjacent the hub, said pawl and the hub having co-acting means for holding the hub in adjustment, and lock-controlled means for locking the pawl against retraction from the holding position. 120

4. In switch operating means, a rockably mounted shaft, a switch operating arm se- 130

cured on said shaft, a handle structure including a hub secured on the shaft and provided with spaced recesses, a holding member movable toward and away from the hub and having an element disposed to project into the recesses of the hub for securing it in adjustment about its axis the recess and the pawl being relatively shaped to exert an outward force on the pawl upon the application of pressure thereto by the hub, and lock controlled means for securing the holding member inoperative.

5. In switch operating means, a supporting base, a shaft rockably mounted in the base, a switch operating arm secured on said shaft, a handle structure including a hub secured on the shaft and having spaced recesses, a holding pawl mounted in the base and having an element disposed to project into said recesses, said pawl being urged toward the hub, and lock controlled means for locking the pawl in position in the recess.

6. In switch operating means, a supporting base, a shaft rockably mounted in the base, a switch operating arm secured on said shaft, a handle structure including a hub secured on the shaft and having spaced recesses, a holding pawl mounted on the base and having an element disposed to project into said recesses, said pawl being urged toward the hub and the element of the pawl being shaped to be forced out of the recess by contact with the wall thereof upon turning of the shaft in either direction under appreciable pressure, and lock controlled means for securing the pawl in operative position.

7. In switch operating means, a supporting base, a shaft rockably mounted in the base, a switch operating arm secured on said shaft, a handle structure including a hub secured on the shaft and provided with spaced recesses, a holding pawl disposed for engagement into said recesses and urged toward the hub, a key operated lock, and a locking member operated by the lock and movable thereby into and out of position to hold the pawl in position in the recess.

8. In switch operating means, a supporting base, a shaft rockably mounted in the base, a switch operating arm secured on the shaft, a handle structure including a hub secured on the shaft and provided with radially disposed recesses, a pawl mounted in the base and having an element disposed for engagement into said recesses, the pawl being urged toward the hub, a cam member mounted in the base for movement into and out of position to hold the pawl against retraction from the hub, a lock mounted in the base, and operating connections between the cam and the lock.

9. In switch operating means, a rockably mounted shaft, a switch arm secured on the shaft, a handle structure including a hub secured on the shaft and having recesses, a pawl

yieldingly urged toward the hub and having an element engageable into said recesses and shaped to be forced out of the same by contact of the walls of the recess with said element under appreciable pressure, a cam mounted and disposed for movement into and out of position to hold the pawl in operative position, and yielding means urging the cam into pawl holding position.

10. In switch operating means, a rockably mounted shaft, a switch arm secured on the shaft, a handle structure including a hub secured on the shaft and having recesses, a pawl yieldingly urged toward the hub and having an element engageable into said recesses and shaped to be forced out of the same by contact of the walls of the recess with said element under appreciable pressure, a cam mounted and disposed for movement into and out of position to hold the pawl in operative position, yielding means urging the cam into pawl holding position, and a lock having operating connection with the cam for moving it into inoperative position and securing it in operative position.

11. In switch operating means, a rockably mounted shaft, a switch arm secured on the shaft, a handle structure including a hub secured on the shaft and having recesses, a pawl having an element engageable into said recesses, means for optionally preventing complete entry of said element into a selected one of said recesses, a cam mounted and disposed for movement into and out of position to hold the pawl in operating position, a key operated lock having a movable key receiving member, and operating connections between said member and the cam.

12. In an electric switch, switch operating means, a pawl normally urged into a position to prevent the operation of the switch, said pawl being retractable from said position responsive to the attempted operation of said means, and key operated locking means for preventing the retraction of the pawl.

13. In an electric switch having a predetermined number of selectively operated positions, a pawl normally urged into a position to prevent the operation of the switch from any one of the selective positions in which it happens to be, said pawl being retractable from said position responsive to an attempted operation of said switch, said pawl being ineffective while the switch is in a position intermediate an operated position, and automatically effective upon the switch reaching an operated position, and key operated locking means for preventing the retraction of the pawl.

14. In an electric switch having a predetermined number of selectively operated positions, and a number of spaced recesses, one for each position of the switch, a pawl normally urged into said recesses and retractable responsible to an attempted operation of the

- switch, and key operated locking means for preventing the retraction of the pawl and thereby locking the switch in position.
15. A switch operating mechanism for a gang switch comprising a movable member for operating a gang switch, a shaft for operating said member, locking means for the shaft, said locking means being biased to hold the shaft against movement, and a key controlled means selectively operable to prevent or to permit release of the locking means.
16. A switch operating mechanism for a gang switch comprising a movable member for operating a gang switch, a shaft for operating said member, locking means for the shaft, said locking means being biased to hold the shaft against movement, a key controlled means selectively operable to prevent or to permit release of the locking means, and means controlled responsive to an attempted operation of the shaft for releasing the locking means when the key controlled means has been operated to permit such release.
17. A switch operating mechanism for a gang disconnect switch comprising a movable member for operating a gang switch, a handle structure including a hub mounted for turning movement and operatively connected to said member, a pawl, said hub and said pawl having coacting means for locking the hub in adjustment, and positive acting means for locking the pawl in its locking position.
18. A switch operating mechanism for a gang disconnect switch comprising a movable member for operating a gang switch, a handle structure including a hub mounted for turning movement and operatively connected to said member, a pawl, said hub and said pawl having coacting means for locking the hub in adjustment, and positive acting means for locking the pawl in its locking position, said last named means being key controlled for releasing the pawl.
19. A switch operating mechanism for a disconnect switch, adapted to be operated only on an open circuit, said mechanism comprising an operating member for operating a disconnect switch, a pawl for locking the member against movement, said pawl being biased to the locking position, cam means for holding the pawl in its locked position, and electromagnetic means effective under predetermined conditions for preventing the release of said pawl.
20. A switch operating mechanism for a disconnect switch adapted to be operated only on an open circuit, said mechanism comprising an operating member for operating a disconnect switch, a pawl for locking the member against movement, said pawl being biased to the locking position, means effective upon an attempted movement of the operating member for exerting a force on the pawl tending to retract the pawl, and electromagnetic
- means effective under predetermined conditions for preventing the release of said pawl.
21. A switch operating mechanism for a disconnect switch adapted to be operated only on an open circuit, said mechanism comprising an operating member for operating a disconnect switch, a pawl for locking the member against movement, cam means for holding the pawl in its locked position, key controlled means for releasing the cam to permit retraction of the pawl, and electromagnetic means effective under predetermined conditions for rendering the key controlled means ineffective to permit operation of said operating member.
22. A disconnect switch operating mechanism comprising a supporting base, a pair of arms projecting from said base, bearings journaled in said arms, a shaft mounted in said bearings, a disconnect switch operating mechanism connected to said shaft and operated thereby, a handle structure including a hub mounted on said shaft for actuating the same, cam means for releasably locking the handle against movement, and key control means for releasing the cam means.
23. A disconnect switch operating mechanism comprising a supporting base, a pair of arms projecting from said base, bearings journaled in said arms, a shaft mounted in said bearings, a disconnect switch operating mechanism connected to said shaft and operated thereby, a handle structure including a hub mounted on said shaft for actuating the same, cam means for preventing actuation of the shaft, and means controlled by the handle for releasing the cam means.
24. A disconnect switch operating mechanism comprising a supporting base, a pair of arms projecting from said base, bearings journaled in said arms, a shaft mounted in said bearings, a disconnect switch operating mechanism connected to said shaft and operated thereby, a handle structure including a hub mounted on said shaft for actuating the same, cam means for preventing actuation of the shaft, means controlled by the handle for releasing the cam means, and key controlled means for controlling the release of said cam means by the handle.
25. A disconnect switch operating mechanism comprising a supporting base, a pair of arms projecting from said base, bearings journaled in said arms, a shaft mounted in said bearings, a disconnect switch operating mechanism connected to said shaft and operated thereby, a handle structure including a hub mounted on said shaft for actuating the same, cam means for preventing actuation of the shaft, means controlled by the handle for releasing the cam means, and electromagnetic means for controlling the release of said cam means by the handle.
26. A disconnect switch operating mechanism comprising a supporting base, a pair of

arms projecting from said base, bearings journaled in said arms, a shaft mounted in said bearings, a disconnect switch operating mechanism connected to said shaft and operated thereby, a handle structure including a hub mounted on said shaft for actuating the same, cam means for preventing actuation of the shaft, means controlled by the handle for releasing the cam means, electromagnetic means and separate key controlled means each controlling the release of said cam means by the handle.

27. A switch operating structure comprising a handle having a hub mounted for turning movement, a switch operating arm having operative connection with the hub, a holding pawl adjacent the hub, said pawl and the hub having coacting means for holding the hub in adjustment and being shaped to force the pawl out of engagement with the hub upon the application of pressure thereto by the hub, and means for locking the pawl against retraction from the holding position by the hub.

28. A switch operating mechanism comprising a handle structure including a hub mounted for turning movement, a switch operating arm having operative connection with the hub, a holding pawl adjacent the hub, said pawl and the hub having coacting means for holding the hub in adjustment, said hub constituting means for retracting the pawl, and lock-controlled means for securing the pawl against retraction from the holding position.

29. A switch operating mechanism comprising a supporting base, a shaft rockably mounted in the base, a switch operating arm secured on said shaft, a handle structure including a hub secured on the shaft and having spaced recesses, a holding pawl mounted in the base and having an element disposed to project into said recesses, said pawl being urged toward the hub, and lock-controlled means for securing the pawl in operative position, said recesses urging the pawl outward upon the application of a turning force on the hub.

30. A switch operating mechanism comprising a supporting base, a shaft rockably mounted in the base, a switch operating arm secured on said shaft, a handle structure including a hub secured on the shaft and provided with spaced recesses, a holding pawl disposed for engagement into said recesses and urged out of engagement therewith by the hub structure, said pawl being biased toward the hub, a key operated lock, and a locking member operated by the lock and movable thereby into and out of position to hold the pawl in its operative position.

In witness whereof, we hereunto subscribe our names this 9th day of September, 1927.

ALFRED ALSAKER.
ERIC NORDHEM.
